WATCH HAND OR SIMILAR ARTICLE

Hans-Ulrich Klingenberg, Merzlingen, Switzerland, assignor to Vacuum Chronometer Corporation, Biel, Switzerland

Filed June 23, 1966, Ser. No. 2,793

Claims priority, application Switzerland Jan. 21, 1966

Term of patent 14 years

(Cl. D42—1)

FIG. 2

FIG. 5

FIG. 6

FIG. 1 is a plan view of my new design for a watch hand as applied to a minute hand wherein the hand is relatively long and consists of two spaced-apart bars extending on both sides of the pivot point;

FIG. 2 is a transverse sectional view taken along line II-II of FIG. 1;

FIG. 3 is a sectional view taken along line III-III of FIG. 1;

FIG. 4 is a plan view of a modified form of the design shown in FIG. 1 as applied to an hour hand wherein the hand is of shorter length and consists of three spaced-apart bars extending on both sides of the pivot point;

FIG. 5 is a transverse sectional view taken along line V-V of FIG. 4;

FIG. 6 is a sectional view taken along line VI-VI of FIG. 4.

I claim:

The ornamental design for a watch hand or similar article, substantially as shown and described.
